(57) **CLAIM**

The ornamental design for a putter head with heel and toe weight arrangements, substantially as shown and described.

DESCRIPTION

FIG. 1 is a top isometric view showing a trailing side of a putter head with heel and toe weight arrangements; FIG. 2 is a back elevation view showing the trailing side of the putter head with the heel and toe weight arrangements; FIG. 3 is a front elevation view showing a leading side of the putter head with the heel and toe weight arrangements; FIG. 4 is a side elevation view showing a heel of the putter head with the heel and toe weight arrangements; FIG. 5 is a side elevation view showing a toe of the putter head with the heel and toe weight arrangements; FIG. 6 is a top plan view of the putter head with the heel and toe weight arrangements; and, FIG. 7 is a bottom plan view of the putter head with the heel and toe weight arrangements. The broken lines in FIGS. 1-7 illustrate a portion of a putter shaft forming no part of the claimed design.

1 Claim, 5 Drawing Sheets
